DESIGN FOR A VACUUM CLEANER CASING

Clifford Brooks Stevens, Milwaukee, Wis., assignor to Modern Hygiene, Inc., Boston, Mass., a corporation of Massachusetts

Application December 22, 1945, Serial No. 125,009

Term of patent 14 years

(Cl. D9—2)

To all whom it may concern:

Be it known that I, Clifford Brooks Stevens, a citizen of the United States residing at Milwaukee, in the county of Milwaukee and State of Wisconsin, have invented a new, original, and ornamental Design for a Vacuum Cleaner Casing, of which the following is a specification, reference being had to the accompanying drawing, forming part thereof.

Figure 1 is a perspective view of a vacuum cleaner casing showing my new design.

Figure 2 is a side elevational view of the same; and

Figure 3 is an end view thereof showing the end of the casing opposite that disclosed in Figure 1.

Both sides and ends of the vacuum cleaner casing are the same and the bottom is plain.

The essential features of my design reside in the parts shown in full lines.

I claim:

The ornamental design for a vacuum cleaner casing, as shown and described.

CLIFFORD BROOKS STEVENS.
